UNITED STATES PATENT OFFICE.

LEWIS E. TROUTMAN, OF SCHENECTADY, NEW YORK, ASSIGNOR TO GENERAL ELECTRIC COMPANY, A CORPORATION OF NEW YORK.

FUSE-BOX.

No. 866,090.

Specification of Letters Patent.

Patented Sept. 17, 1907.

Application filed November 11, 1905. Serial No. 286,871.

To all whom it may concern:

Be it known that I, LEWIS E. TROUTMAN, a citizen of the United States, residing at Schenectady, county of Schenectady, and State of New York, have invented 5 certain new and useful Improvements in Fuse-Boxes, of which the following is a specification.

This invention relates to thermal cut-outs, and its object is to provide a compact device of this class that is simple in construction, strong and durable, and capable 10 of handling heavy currents.

The invention consists in a fuse-box containing line-terminals provided with clips, and a removable fuse-carrying block of novel construction, as hereinafter set forth and particularly pointed out in the claims.

15 In the accompanying drawing, Figure 1 is a longitudinal section of a fuse-box embodying my invention, taken on the line 1—1, Fig. 3, and looking from below; Fig. 2 is a similar section, on the line 2—2, Fig. 3; Fig. 3 is a cross-section through the center of the box, and on 20 the line 3—3 of Fig. 4; Fig. 4 is a longitudinal section of the fuse-carrying block, on the line 4—4, Fig. 3.

The box 1 may be of cast metal, with lugs 2 for securing it to a suitable support. It has a hinged front 3, which is preferably provided with a spring bolt 4 for 25 fastening it. An overhanging flange 5 prevents rain and dust from entering the joint when the box is exposed to the weather. In the bottom is an opening 6 to permit the escape of gases when the fuse blows. Near each end of the bottom at the rear is an opening 30 provided with an insulating bushing 7 for the line terminal, which is received in a metallic socket 8 provided with a binding screw 9 and located in a recess in a plate 10 of insulating material secured to the back of the box. Each socket has an arm 11 extending over the base of a 35 sheet-metal clip 12 and receiving a screw 13 by which the clip and socket are secured in place. The clip is preferably a U-shaped strip of metal having in-turned ends, and it is preferably seated in a shallow recess in the plate 10 adjacent to that recess in which the socket 40 8 is held.

The fuse-carrier 14 is a block of porcelain or the like having a handle 15, and provided with two recesses in its upper side separated by a barrier 16, and a single longer recess in its lower side. The upper recesses are 45 covered by a plate 17 of insulating material, held in place by a screw 18 meshing with a nut let into the barrier 16. In each of the upper recesses is a metallic blade 19, adapted to enter one of the clips 12, and secured in place by a bolt 20 which passes through the

block and through the end of the lower recess, where it 50 is provided with a securing-nut 21, and also with a washer 22 and a clamping nut 23: the latter being for the purpose of clamping one end of the fuse-strip 24 which electrically connects the two blades 19.

The fuse-strip 24 is covered by a block 25 of insulating material having a recess in its upper side into which is snugly fitted a block 26 of insulating material which is held in the middle portion of the recess in the fuse-carrier. Both of the blocks 25, 26 are preferably made of lignum vitae, and have cavities which register, so 55 that there is formed a chamber inclosing the middle portion of the fuse-strip. A hole 27 in the block 25 connects this chamber with a flaring mouth 28 which opens in line with the opening 6 in the bottom of the box and forms an arc chute. The blocks 25, 26 are clamped to 60 the fuse-carrier by knobs 29 screwed on the projecting ends of the bolts 20. The knobs are preferably made of porcelain with a filling 30 of metal in which the screw threads are tapped.

When it becomes necessary to replace a blown fuse, 70 the operator unlocks and turns down the front of the box, and then grasps the handle 15 and pulls out the fuse-carrier. On unscrewing the knobs 29, the block 25 can be taken off, giving access to the clamping nuts 23, which can then be loosened to release the unconsumed 75 ends of the old fuse. The fresh fuse is then laid across the block 26 and its ends are clamped in place by the nuts 23. The block 25 is then replaced and the knobs 29 screwed on, the over-lapping edges of the block 26 and the recess in the block 25 operating to crimp the 80 fuse at each end of the central chamber, so that all the gas produced by the melting of the fuse will be compelled to blow out through the arc chute. The fuse-carrier is then inserted in the box, the blades 19 entering 85 the clips and closing the circuit between the line terminals.

It will be observed that the metallic parts of the fuse-carrier are completely inclosed, so that it can be handled with entire safety. Moreover, the arc chute is directed away from the handle of the carrier, so that 90 there is less liability of injury to the operator in case the fuse blows when the carrier is replaced in the box.

What I claim as new and desire to secure by Letters Patent of the United States, is,—

1. In a fuse-box, a fuse-carrier comprising a block having recesses in opposite sides and a handle at one edge, contact blades in the recesses on one side and parallel to the plane of said side, an inclosed fuse in the recess on the

opposite side, and bolts passing through said block and connecting said blades and fuse.

2. In a fuse-box, a fuse-carrier comprising a block of insulating material having in one side two recesses separated by a barrier, and in the opposite side a single recess, contact blades in the two recesses on one side, holding bolts for said blades passing through said block into the ends of the recess on the opposite side, fuse-clamping nuts on said bolts, a block of insulating material in the recess

between said bolts said block having a cavity, a cover-block having a registering cavity and holes for said bolts, and knobs on the ends of said bolts.

In witness whereof, I have hereunto set my hand this 10th day of November, 1905.

LEWIS E. TROUTMAN.
